Samuel Doskow
BY
Nathan I. Adler
ATTORNEY

UNITED STATES PATENT OFFICE.

SAMUEL DOSKOW, OF NEW YORK, N. Y.

DENTAL ATTACHMENT FOR REMOVABLE BRIDGES AND CLASP DENTURES.

Application filed March 5, 1923. Serial No. 623,072.

To all whom it may concern:

Be it known that I, SAMUEL DOSKOW, a citizen of the United States of America, residing at New York city, in the county of New York and State of New York, have invented certain new and useful Improvements in Dental Attachments for Removable Bridges and Clasp Dentures, of which the following is a clear and exact specification, reference being had therein to the accompanying drawing.

My invention relates to removable bridges and clasp dentures, and more particularly to the application and construction of stress-breaking attachments for the clasps.

The attachment forming the substance of this invention consists of a linking member permanently mounted on the clasp and a socket member fixedly supported on the removable bridge or denture, the combination of the linking and socket members acting as the means for permanently joining the clasp to the removable bridge or denture. This attachment may be used with any type or form of dental clasp that is adapted to support a removable bridge or denture in the mouth. The stationary tooth in the mouth to which the clasp is gripped is termed its "abutment."

The principal object of my invention is to provide an attachment for the clasps of removable bridges or dentures, wherein the stress on the removable bridge or denture due to mastication and similar natural causes, is absorbed by the ability of the removable bridge or denture to function with a restricted universal movability relative to its fixed abutments, by virtue of the construction of the linking and socket members of the attachment. That is, where ordinarily the mastication stresses are absorbed in frictional movement or play of the clasp against the contact surface of its abutment, with its attendant ill effects, it has been the object herein to provide such an attachment, whereby these stresses are absorbed by the universal free play or movement acquired by the removable bridge or denture relative to its stationary abutments, this said universal free movement being restricted and equivalent to the natural tooth movement during mastication.

A further object of my invention has been the provision of a dental clasp stress-breaking attachment simple and strong in construction, and positive in action.

In view of the aforesaid objects, and the further objects obvious in the description following, the dental clasp stress-breaking attachment forming the substance of this invention consists of the novel features of construction and arrangement and combination of parts, hereinafter described and illustrated, and as particularly set forth in the claims appending this specification.

In the accompanying drawing I have illustrated a preferred embodiment of my invention, to attain the aforementioned objects, in which similar reference characters indicate corresponding parts in the various views.

In the accompanying drawing:

Figure 1 is a perspective view of the socket member of the attachment.

Figure 2 is a perspective view of the cover for closing the top opening of the socket member.

Figure 3 is a perspective view of the linking member of the attachment.

Figure 4 is an elevation of a two-tooth removable bridge or clasp denture, in position between its abutments, showing both the socket and linking members of one attachment in lateral section.

Figure 5 is a fragmentary view of the removable bridge or clasp denture, showing a plan section taken midway through both the socket and linking members of one attachment and its clasp.

The linking member of my attachment consists of the head element 1, having formed thereto the shoulder bar 2, which in turn terminates into the slightly curved web element 3. Although the formation of the shoulder bar 2 to the head element 1 and web 3 is shown, in each instance in the accompanying drawing, to be at an angle of (90) degrees, these angles may be of values other than (90) degrees, and of dissimilar magnitudes, to suit specific cases. The head element 1 is formed, referring to Figures 3, 4 and 5, oval or egg-shaped, with the front and rear surfaces, i. e., that portion of the surface opposite to the shoulder junction and the portion of the surface adjacent to the shoulder junction, respectively, somewhat flattened. In addition, the front surface recedes just sufficiently from the center towards the lateral extremities, forming a slightly curved eminence extending vertically along the central portion of the front surface of the head element. It is prefer-

able to have the head element 1, the shoulder bar 2, and the web 3 formed in one piece, as the linking member is applied to the artificial denture with the application of heat.

5 The socket member of the attachment consists of a flat metallic sheet bent to form an elliptically shaped wall 4, referring to Fig. 1, the wall having positioned centrally the slot 5, extending the full length thereof. 10 The lower terminus of the socket wall 4 is provided with the flat bottom 6, which may be an integral part of the wall, or a piece separate from the wall and soldered thereto. The upper terminus of the socket wall 4 is provided with the flat top 7, which is permanently positioned (soldered) in place, after the linking member has been finally made to engage within the socket member. The overall height of the head element 1 20 is a trifle less than the internal height of the socket wall 4, giving to the linking member, after it has been finally made to engage within the socket member, a slight up and down movement. 25 The curvature of that section of the socket wall 4 opposite to the slot 5, i. e., that section of the wall co-operating with the eminence portion of the head 1, is such as to correspond to the contour of the eminence portion of the head, but with a somewhat greater sweep of arc. Thus, when the head element 1 of the linking member is made to engage within the socket member, and the top 7 fixed in position, the linking 30 member will be possessed of a restricted movement or play in any direction, i. e., a restricted universal movement. The elliptically shaped opening formed by the socket wall 4 is of uniform section throughout the 35 full height of the wall. 40

In Fig. 4 I show a two clasp removable bridge or denture, composed of an artificial first molar 8 and second bicuspid 9, supported between the natural second molar 10 and natural first bicuspid 11, each clasp being provided with the stress-breaking attachment. The first molar 8 and second bicuspid 9 are permanently mounted on the bridge saddle structure 12, the second molar 10 and first bicuspid 11 acting as the 45 abutment teeth therefor.

The socket member of each attachment is permanently positioned (soldered) onto the saddle structure 12. The linking member of each attachment is permanently mounted (soldered) to its respective clasp 13, reference being had to Figures 4 and 5. The linking member of each attachment is then seated within its respective socket member, and a top cover 7 is fixed in position, soldered, over the upper terminus of each 50 socket member.

The clasps 13 will now permanently be supported to the saddle structure 12, and 55 by virtue of their connection to the linking

members, will also be possessed of a restricted universal movement. However, when the removable bridge or denture is seated in position between its abutments in the mouth, in this instance the clasps 13 gripping the second molar 10 and first bicuspid 11 acting as the abutment teeth, this restricted universal movement relative to the fixed abutments will now be possessed by the removable bridge or denture instead, for the clasps will then be held tightly gripped to the respective abutment teeth by their inherent tension-ability. Thus, the stresses due to mastication and similar natural functions that are ordinarily absorbed by the frictional movement of the clasp against the contact surface of the abutment tooth are here absorbed by the restricted universal movement or play of the removable bridge or denture. 85

The method of supporting the socket members on the removable bridge or denture and the method of mounting the linking members on the clasps, as referred to in the foregoing, is understood to be carried out in the manner well known to those skilled in the art and technique of this branch of dentistry. Although I have illustrated and described in the foregoing, a removable bridge or denture consisting of two artificial teeth and two clasps and their attachments, this has been chosen arbitrarily to illustrate a particular case. The number of clasps and their attachments to be used for a removable bridge or denture is generally two 90 or more than two, depending on the restoration. 95

I wish to set forth that the sizes of the attachments may be different, even for the same removable bridge or denture, where it is necessary to accommodate widely different types of teeth. The material for fabricating these attachments may be any non-corrosive metal, preferably a platinum-gold alloy. Both members of the attachments 100 may be constructed of similar material or otherwise.

Herein I have illustrated and described a practical embodiment of my invention in considerable detail, and I wish to set forth 115 that modifications and changes thereof may be readily resorted to without departing from the spirit and scope of the invention, as expressed in the appended claims.

What I claim is:

1. A dental attachment for removable bridges and clasp dentures, comprising an oval or egg-shaped head linking member adapted to be permanently mounted on the clasp, and an elliptically shaped socket member with a closed top and closed bottom adapted to be permanently secured on the removable bridge or denture; the said linking member engaging permanently within the said socket member and acting 125 130 135

as the means for permanently joining the said clasp member in restricted universally movable relationship to the removable bridge or denture, substantially as set forth.

5. 2. A dental attachment for removable bridges and clasp dentures, comprising a linking member composed of an oval or egg-shaped head element, of a shoulder bar element formed integrally thereto the said 10 head element at an angle, and a web formed integrally thereto the said shoulder bar at an angle, a socket member formed of an elliptically shaped wall closed at the bottom and having positioned centrally a narrow 15 slot extending the full length thereof the said wall, and a top cover element for the said socket member; the linking member engaging permanently within the walled area of the socket member with the said shoulder 20 bar disposed in the slotted section of the socket wall.

3. A stress-breaking dental attachment for removable bridges and clasp dentures, comprising a linking member composed of 25 an oval or egg-shaped head element with front and rear surfaces somewhat flattened and having disposed vertically along the central portion thereof, the front surface, a slightly curved eminence, on a shoulder bar

element integrally formed on the rear part 30 of the head element, vertically and centrally, and of a slightly curved web element formed integrally on the said shoulder bar, a socket member formed of an elliptically shaped wall slotted vertically and 35 provided with covers for closing the top and bottom openings; the said linking member seating permanently within the said socket member and unitedly forming the means for permanently joining the clasp 40 member in restricted movable relationship to the removable bridge or denture.

4. A stress-breaking dental attachment for removable bridgework or clasp dentures, comprising a linking member composed of a head element a shoulder bar element and web element all integrally formed and adapted to be permanently secured to the clasp member, a closed bottom socket member formed of a slotted elliptically shaped 50 wall adapted to be permanently supported on the saddle structure of the removable bridge or denture, and a cover element adapted to permanently close the top opening of the said socket member after the head 55 element of the linking member has been seated therein.

SAMUEL DOSKOW.
